UNITED STATES PATENT OFFICE

2,645,030

INCLINOMETER

Thomas L. Mahone, Hampton, Va.

Application November 8, 1951, Serial No. 255,477

1 Claim. (Cl. 33—206)

1

This invention relates to new and useful improvements in instruments for airplanes and the like and the primary object of the present invention is to provide an inclinometer mountable on the dash panel of an airplane to indicate whether or not the ship is on an even keel or to what degree and to what direction it is inclined.

Another object of the present invention is to provide an inclination indicator for indicating the position of an airplane with respect to the ground and the direction of travel, and which is so graduated as to permit an instant reading at all positions on the globe above and below a horizontal plane.

A further object of the present invention is to provide an inclinometer capable of finding or measuring accurately two intersecting planes lying on the same plane and of different degrees.

A still further aim of the present invention is to provide an instrument of the aforementioned character that is simple and practical in construction, strong and reliable in use, efficient and durable in operation, inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the present invention;

Figure 2 is a side view of Figure 1;

Figure 3 is a vertical sectional view taken substantially on the plane of section line 3—3 of Figure 1; and,

Figure 4 is a horizontal sectional view taken substantially on the plane of section line 4—4 of Figure 2.

Referring now to the drawings in detail, wherein for the purpose of illustration, there is disclosed a preferred embodiment of the present invention, the numeral 10 represents a hollow transparent outer sphere that is suitably secured to upwardly inclined corner supporting arms 12 rising from a substantially square base 14 having two intersecting center lines 16 and 18 across its top and sides, indicating two distinct directions.

An inner sphere 20 is secured centrally within the sphere 10 by spacers 22 to retain the inner periphery of the sphere 10 spaced from the outer periphery of the sphere 20, thereby forming a chamber 24 in which a liquid 26 is placed. The

liquid fills all but a small portion of the chamber 24 to provide an air bubble 28.

The sphere 10 is formed with an opening that is sealed after the liquid 26 has been placed in the sphere 10. The spheres 10 and 20 may be in halves that are suitably secured and sealed together or suitable construction methods may be followed to fix the sphere 20 within sphere 10.

The sphere 20 is provided with three sets of circles 30, 32 and 34. The circles 30 are disposed in horizontally spaced vertical planes and the circles 32 are disposed in vertically spaced horizontal planes. Circles 34 are disposed in horizontally spaced vertical planes that intersect the planes of the circles 30 at right angles.

The largest circle of the circles 30 meet the largest circle of the circles 34 at the center of the top circle of the circles 32, indicated by 36. The circles 30 are spaced equally apart and are provided with indicia from 0° to 180° left to right and also from right to left starting at point 36. The circles 30 are also provided with indicia from 180° to 0° from left to right and also from right to left starting at point 36.

The circles 34 are also provided with indicia from 0° to 180° from top to back and from top to front starting from point 36. The circles 34 are also provided with indicia from 180° to 0° from top to back and from top to front starting at point 36.

Base 14 may be readily secured to the dash panel of an airplane by fasteners or the like. The air bubble 28 will shift in response to directional or inclination changes in the airplane and such inclination may be readily determined by reading the graduations on the circles adjacent the bubble.

Having described the invention, what is claimed as new is:

40 An inclination indicator for airplanes and the like comprising an outer transparent sphere having graduations on its exterior surface, an inner sphere fixed within and held stationary with respect to the outer sphere, a leveling liquid within the outer sphere about the inner sphere, said liquid and said inner sphere occupying all but a small part of the interior of said outer sphere in order to form an air bubble for registering with the graduations on said outer sphere, said outer sphere being provided with a first series of circles lying on horizontally spaced vertically disposed planes, a second series of circles also provided on said outer sphere and lying on vertically spaced horizontal planes, and a third series of circles also provided on said outer sphere and

50 55

lying on horizontally spaced vertical planes disposed perpendicular to the planes of the first and second series of circles, the circles of each series being spaced apart 10° from each other, a substantially square base underlying the outer sphere, corner supporting arms terminally secured to the outer sphere and the corners of the base to support the outer sphere above the base, said base having an upper face with two relatively perpendicular intersecting center lines thereon to represent two different directions.

THOMAS L. MAHONE.
